of DelawareApplication June 27, 1934, Serial No. 732,570
Renewed February 6, 1936

15 Claims. (Cl. 250—27.5)

My invention relates to improvements in methods and means for making a photosensitive device.

For the purpose of developing picture signals for television transmission, it has been proposed to mount a mosaic, photosensitive screen in an evacuated tube, to project onto the screen an image of the object, and to scan the screen with a cathode ray. In the development of these tubes, one of the problems has been in the construction of the screen and the step of photosensitizing the mosaic surface thereof. The essential characteristics of such a screen are that the same consist of a great number of minute, conductive, photosensitized elements disposed over a surface of a supporting base member, each element being spaced and insulated from the others. In one type of television transmitting tube, the supporting base member for the screen has been in the form of a thin sheet of mica provided on one side thereof with a metallic coating to which an output connection is made, and on its other side with the mosaic of the elements referred to, each of the photosensitive elements, with the metallic layer, constituting a minute condenser.

In operation, an image of the object is projected onto the photosensitive surface, causing emission of electrons therefrom and development accordingly of electrostatic charges over the surface, the magnitude of any particular charge being proportional to the light intensity on the respective elemental area of the screen.

For most satisfactory results, it is important that the charges referred to accumulate linearly and be retained and, to this end, it is essential that no leakage shall occur between adjacent elements or elemental areas of the screen. In this connection, the screens referred to are photosensitized by first oxidizing the metallic elements and then generating within the tube a vapor of an alkali metal, such as caesium, and in amount somewhat in excess of that required. In this way, and if silver is used, the silver oxide is reduced to metallic silver, the oxygen combining with the caesium to form one or a mixture of the various oxides of caesium so that each individual element is provided with a coating of caesium oxide which serves to effectively bind a layer of caesium of monatomic dimensions.

The tube is then baked and pumped to remove the excess caesium, and obtain the maximum degree of sensitivity, after which the temperature is reduced to room temperature.

During the step of introducing caesium into

the tube, free or loosely bound caesium unavoidably condenses on the insulating mica surface between the individual elements, thereby connecting them electrically. It seems that most of this caesium is removed during the baking and pumping step, but at any rate, enough remains to constitute at least some degree of short-circuiting path between the adjacent elements to prevent them from storing the electrostatic charges linearly and retaining the charges. The remaining caesium could be removed by continued baking and pumping, but in doing this the temperature would have to be relatively low to prevent removal of the desired monatomic layer of caesium on the individual elements. Under such conditions, an undesirably long period of pumping would be necessary, during which conditions might occur to impair the photosensitivity previously obtained.

With the foregoing in mind, it is one of the objects of my invention to provide an improved method and means of making a photosensitive device of the character referred to whereby the insulating surface between the individual photosensitized elements is entirely cleaned of any short-circuiting material which might remain after completion of the photosensitizing step.

Other objects and advantages will hereinafter appear.

In accordance with my invention, an agent capable of absorbing photosensitive material is placed within the tube and isolated against absorbing action with respect to the material. A vapor of the photosensitive material is then generated within the tube to photosensitize the screen, after which the tube is baked to obtain the maximum degree of photosensitivity. The agent referred to is then released to absorb any photosensitive material which might have remained on the insulating surfaces between adjacent elements whereby the resistance between the latter is made as near infinity as possible.

More specifically, in accordance with my invention, a column, to the surface of which has been applied a coating of material capable of absorbing the photosensitive material, is supported within the tube. A sheet of material such as mica is wrapped about the column to cover the absorptive material and isolate the same against absorbing action with respect to the photosensitive material. Means including a fusible element in the form of a fine wire operates to hold the mica sheet wrapped about the column. After the photosensitizing step a voltage is applied to the wire to fuse the same, where-

upon the mica sheet referred to is permitted to unfold from about the column and expose the absorbing agent which is then effective to absorb any free caesium still remaining on the 5 mica surface between the minute photosensitive elements.

My invention resides in the improved method and means of the character hereinafter described and claimed.

10 For the purpose of illustrating my invention, an embodiment thereof is shown in the drawing, wherein

15 Figure 1 is an elevational view, partly broken away, of a cathode ray transmitting tube provided with the construction and means for carrying out my improved method;

Fig. 2 is an enlarged, fragmentary, sectional view, the section being taken on the line 2—2 in Fig. 1;

20 Fig. 3 is a view similar to Fig. 2, showing the condition of the respective parts after carrying out my improved method; and

25 Fig. 4 is an enlarged, fragmentary, sectional view of the mosaic photosensitive screen, the section being taken on the line 2—2 in Fig. 1.

In the drawing the reference numeral 10 designates a cathode ray transmitting tube for television, provided with a screen 12 and means 14 of conventional construction for developing a ray 16 of electrons and directing the ray at the screen. The screen comprises a supporting base member in the form of a sheet 18 of mica provided on the back surface thereof with a metallic coating 20, and on its front surface with a great number of 30 minute metallic elements 22 arranged in the form of a mosaic and each spaced from the others. The screen is supported at its four corners by wires 24 extending outwardly from a column 26 supported within the tube from a reentrant portion 28 of the wall structure.

Each of the metallic elements 22 is oxidized to provide the same with a coating 30 of the oxide of the metal. In carrying out the photosensitizing step, a capsule 38 previously placed within 45 the tube is carried by the supporting wire 34 attached to the wire 52, and containing an alkali metal such as caesium, is exploded to generate a vapor of the alkali metal. A coating 32 of caesium oxide is thus caused to form on each of the elements 22 and a photosensitive layer of caesium is bound to this coating. During this step free or 50 loosely bound caesium, indicated at 34 in Fig. 4, condenses on the mica surface between the individual elements 22 to connect them electrically, thereby making it impossible for these elements to 55 retain an electrostatic charge.

In the next step of photosensitization, the tube is baked and simultaneously pumped to diminish 60 the photosensitive caesium layer to the point of maximum photosensitivity. During the baking and pumping step most of the free caesium previously condensed on the mica surface between the elements 22 is evaporated off, but enough of 65 this free caesium remains to provide at least some degree of leakage paths between the individual photosensitized elements to prevent them from retaining a given charge for a fraction of a second. Continued pumping has not been effective to re- 70 move all of this small amount of free caesium.

For the purpose of removing or cleaning up any remaining free caesium on the mica surface between the elements 22, I propose to apply to the surface of the column 26 a coating 36 of an agent 75 such as lead oxide or stannic oxide capable of ab-

sorbing the caesium. A sheet 38 of mica is wrapped about the column 26 to cover the absorbing agent and isolate the same against absorbing action with respect to the caesium. This sheet is held about the column 26 by complementary metal parts 40 and 41 bent and embracing the column 26 as shown in Fig. 2. These parts are held together about the column 26 by a sheet 42 of mica, for which purpose they are threaded as shown through slits 44 in the sheet 42, and their respective ends are bent around and secured to wires 50 and 52, respectively, to which these ends are welded. The wire 50 is bent as shown and is connected at 54 to the metallic coating 20 of the screen 12, from which this wire extends outwardly through the wall of the tube 10 to provide an output connection from the tube. The wire 52 is bent as shown and extends through the reentrant portion 28 of the tube for the purpose hereinafter explained.

20 The complementary parts 40 and 41 are also held in position about the column 26 by a fine fusible wire 56 connected to the other ends of these parts. One end of the wire 56 is welded directly to the end of the part 41, while the other end of this wire is wrapped about and welded to an L-shape metal piece 58 welded to the end of the part 40.

25 The mica sheet 38, due to its resiliency and tendency accordingly to unfold from about the column 26, might split at its free edge 60 where the part 40 presses against the sheet. To prevent this, it is proposed to weld a short piece 62 of wire to the end of the part 40, this piece of wire 30 extending axially of the column 26 and along the free edge 60 of the mica sheet.

35 During the photosensitizing step explained above, the mica sheet 38 remains wrapped about the coating 36 of lead oxide or stannic oxide so that this agent is not effective to absorb any of 40 the caesium vapor. After this step, a voltage is applied to the connections 50 and 52 to fuse the wire 56 and permit the parts 40 and 41 to spring outwardly and the mica sheet 38 to unfold from 45 about the column 26, as shown in Fig. 3, whereupon the coating 36 is exposed to the atmosphere within the tube 10 and is effective to absorb all 50 of the free caesium which might have remained on the mica surface between the elements 22 or on other surfaces within the tube 10. At this time the tube is at room temperature or somewhat higher, but not sufficiently high to cause evaporation of the photosensitive caesium layers 55 on the elements 22.

From the foregoing it will be seen that by my 55 improved method and means it is possible to employ a clean-up agent after completion of the photosensitizing step, the agent being isolated and ineffective during this step. An important 60 feature of my improved means resides in the fact that the absorbing or cleaning-up action of the agent for this purpose is controlled externally 65 of the tube 10, by making connections to the wires 50 and 52.

70 While my improved method and means has been described more in connection with the construction of a cathode ray tube for television transmission, it has a much broader adaptation, and can be applied in the construction of different types of photosensitive devices where it is desired to remove a certain amount of photosensitive material after the photosensitizing step has been completed.

75 While but one embodiment of my invention has been disclosed, it will be understood that various

modifications, within the conception of those skilled in the art, are possible without departing from the spirit of my invention or the scope of the claims.

5. I claim as my invention:

1. A photosensitive device comprising a tube provided with electrodes one of which is photosensitive, an agent disposed on an interior surface of said tube and capable of absorbing photosensitive material, means covering the surface containing said agent to isolate the same against absorbing action with respect to said material, and means for removing said covering means to expose said agent to the atmosphere within said tube.

2. A photosensitive device comprising a tube provided with electrodes one of which is photosensitive, an agent disposed on an interior surface of said tube and capable of absorbing photosensitive material, means covering the surface containing said agent to isolate the same against absorbing action with respect to said material, and means holding said covering means against said surface.

25. 3. A photosensitive device comprising a tube provided with electrodes one of which is photosensitive, a member supported within said tube and provided on part of its surface with a coating of material capable of absorbing photosensitive material, a sheet of material wrapped about said member and covering said surface to isolate said agent against absorbing action with respect to the photosensitive material, and means holding said sheet wrapped about said member.

35. 4. A photosensitive device comprising a tube provided with electrodes one of which is photosensitive, a column supported within said tube and provided on part of its surface with a coating of material capable of absorbing photosensitive material, a sheet of material wrapped about said column and covering said surface to isolate the absorptive agent against absorbing action with respect to the photosensitive material, and fusible means holding said sheet wrapped about said column.

45. 5. A photosensitive device comprising a tube provided with electrodes one of which is photosensitive, a column supported within said tube and provided on part of its surface with a coating of material capable of absorbing photosensitive material, a sheet of material wrapped about said column and covering said surface to isolate the absorptive agent against absorbing action with respect to the photosensitive material, complementary parts embracing said column and holding said sheet wrapped about the same, and fusible means connected to adjacent ends of said parts and holding the latter in position about said column.

50. 6. A photosensitive device comprising a tube provided with electrodes one of which is in the form of a screen comprising a supporting base and minute photosensitive elements carried thereby and disposed in mosaic fashion over said base and spaced from each other, a member supported within said tube and provided on part of its surface with a coating of material capable of absorbing photosensitive material from the surfaces of said base between the individual photosensitive elements, a sheet of material wrapped about said member and covering said surface to isolate said agent against absorbing action with respect to the photosensitive material, and means holding said sheet wrapped about said member.

75. 7. A photosensitive device comprising a tube

provided with electrodes one of which is in the form of a screen comprising a supporting base and minute photosensitive elements carried thereby and disposed in mosaic fashion over said base and spaced from each other, a member supported within said tube and provided on part of its surface with a coating of material capable of absorbing photosensitive material from the surfaces of said base between the individual photosensitive elements, a sheet of material wrapped about said member and covering said surface to isolate said agent against absorbing action with respect to the photosensitive material, complementary parts insulated from each other and embracing said member and holding said sheet wrapped about the latter, fusible means connected to adjacent ends of said elements and holding the latter in position about said member, and electrical connections from the respective ends of said fusible means and extending through the wall structure of said tube to the exterior thereof for applying a voltage sufficient to cause fusing of said fusible means.

8. A photosensitive device comprising a tube provided with electrodes one of which is photosensitive, an agent disposed within the interior of said tube and capable of absorbing photosensitive material, means covering the said agent to isolate the same against absorbing action with respect to said material, and means for removing said covering means to expose said agent to the atmosphere within said tube.

25. 9. A photosensitive device comprising a tube provided with electrodes one of which is photosensitive, an agent disposed within the said tube and capable of absorbing photosensitive material, means covering the said agent to isolate the same against absorbing action with respect to said material, and means holding said covering means against said agent.

30. 10. A photosensitive device comprising a tube provided with electrodes one of which is photosensitive, a member supported within said tube and provided on part of its surface with a coating of material capable of absorbing photosensitive material, a sheet of material wrapped about said member and covering said surface to isolate said agent against absorbing action with respect to the photosensitive material, and releasable means holding said sheet wrapped about said member.

35. 11. A photosensitive device comprising a tube provided with electrodes one of which is in the form of a screen comprising a supporting base and minute photosensitive elements carried thereby and disposed in mosaic fashion over said base and spaced from each other, a member supported within said tube and provided on part of its surface with a coating of material capable of absorbing photosensitive material from the surfaces of said base between the individual photosensitive elements, a sheet of material wrapped about said member and covering said surface to isolate said agent against absorbing action with respect to the photosensitive material, and releasable means holding said sheet wrapped about said member.

40. 12. A photosensitive device comprising a tube provided with electrodes one of which is photosensitive, a source of supply of photosensitive material, an agent disposed within the interior of said tube and capable of absorbing photosensitive material, means covering the said agent to isolate the same against absorbing action with respect to said material, and means for removing

- said covering means to expose said agent to the atmosphere within said tube.
13. A photosensitive device comprising a tube provided with electrodes one of which is photosensitive, a source of supply of photosensitive material, an agent disposed within the said tube and capable of absorbing photosensitive material, means covering the said agent to isolate the same against absorbing action with respect to said material, and means holding said covering means against said agent.
14. A photosensitive device comprising a tube provided with electrodes one of which is photosensitive, a source of supply of photosensitive material, a member supported within said tube and provided on part of its surface with a coating of material capable of absorbing photosensitive material, a sheet of material wrapped about said member and covering said surface to isolate said agent against absorbing action with respect to the photosensitive material, and releasable
- means holding said sheet wrapped about said member.
15. A photosensitive device comprising a tube provided with electrodes one of which is in the form of a screen comprising a supporting base and minute photosensitive elements carried thereby and disposed in mosaic fashion over said base and spaced from each other, a source of supply of photosensitive material, a member supported within said tube and provided on part of its surface with a coating of material capable of absorbing photosensitive material from the surfaces of said base between the individual photosensitive elements, a sheet of material wrapped about said member and covering said surface to isolate said agent against absorbing action with respect to the photosensitive material, and releasable means holding said sheet wrapped about said member.
